By his Attorneys,

Harris L. Wallace, Inventor

Cadmore & Co.

UNITED STATES PATENT OFFICE.

HARRIS L. WALLACE, OF HALIFAX, CANADA.

DESIGN FOR A WRENCH AND BRACE MEMBER.

SPECIFICATION forming part of Design No. 31,593, dated October 3, 1899.

Application filed January 3, 1899. Serial No. 701,054. Term of patent 3 years.

To all whom it may concern:

Be it known that I, HARRIS L. WALLACE, a subject of the Queen of Great Britain, residing at Halifax, in the Province of Nova Scotia and Dominion of Canada, have invented and produced a new and original Design for a Wrench and Brace Member, of which the following is a specification.

The invention relates to a new and original design for a wrench and brace member; and it has for its object to provide a design of this character that shall be both useful and ornamental.

The leading feature of the design resides in a U-shaped stock having parallel shanks, one of which is provided with a reduced straight squared portion having at its outer terminal an offstanding right-angularly-disposed fixed jaw of a segmental form.

In addition to the essential feature pointed out the design involves several minor features, which are the U-shaped stock, having at the terminal of one of its shanks an offstanding right-angularly-disposed rounded handle extension, and the longitudinally-curved fixed jaw, being of a greater width than the squared shank portion contiguous thereto and provided in its inner curved face with an angular groove leading to the outer extremity thereof.

In the drawings, Figure 1 is a side view of a member of a wrench and brace embodying the herein-described design. Fig. 2 is a sectional view on the line 2 2 of Fig. 1. Fig. 3

is a detail sectional view on the line 3 3 of Fig. 1 looking in the direction of the arrow and exposing the form of the groove or notch in the inner face of the offstanding fixed jaw of the member.

Referring to the accompanying drawings, the numeral 1 designates a U-shaped stock round in cross-section and having oppositely-located parallel shanks 2 and 3, the shank 2 of the stock being provided at its terminal with an offstanding right-angularly-disposed rounded handle extension 4. The other shank 3 of the U-shaped stock is provided with a reduced straight squared portion 5, having at its outer terminal an integral offstanding right-angularly-disposed fixed jaw 6. The fixed jaw 6 is curved in the direction of its length, and is therefore of a segmental form, said fixed jaw being of a greater width than the squared shank portion 5 contiguous thereto and provided in the inner curved face thereof with a longitudinally-disposed angular groove or notch 7, which leads to the outer extremity of the jaw.

What is claimed is—

The design for a wrench and brace member, herein shown and described.

In testimony that I claim the foregoing as my own I have hereto affixed my signature in the presence of two witnesses.

HARRIS L. WALLACE.
